UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

STOCK-HANDLING MACHINE

1,280,349.

Specification of Letters Patent.

Patented Oct. 1, 1918.

Application filed May 18, 1916, Serial No. 98,288. Renewed February 18, 1918. Serial No. 217,951.

To all whom it may concern:

Be it known that I, ERASTUS E. WINKLEY, a citizen of the United States, residing at Lynn, in the county of Essex and State of Massachusetts, have invented certain new and useful Improvements in Stock-Handling Machines; and I do hereby declare the following to be a full, clear, and exact description of the invention, such as will enable others skilled in the art to which it appertains to make and use the same.

This invention relates to machines for operating on pieces of material such, for example, as shoe-stock, and particularly pieces or lifts of leather or other material used in the manufacture of heels. The invention relates more particularly to machines of which the operation involves accurate registration, with the operative instrumentalities, of pieces of stock which are uniform in outline or contour, and the automatic transferral of such pieces, from a supply, to the operative instrumentalities and thence to a point or points of discharge.

One object of the invention, relating particularly to machines provided with means for supporting or retaining pieces of stock at a plurality of positions, is to provide means by which all, or a plurality, of the stock-supporting or retaining means may be adjusted simultaneously, and proportionately or equally, so that the machine may be conveniently and quickly adjusted for operation on pieces of stock of different sizes.

For the purposes of such adjustment the machine of the present invention comprises, in combination with the relatively movable abutments which engage and confine the pieces of stock at a plurality of positions, means interconnecting said abutments, whereby adjusting movements may be imparted to them all simultaneously and from a single point of operation, and in the machine specifically described and illustrated this construction and mode of operation are applied both to the abutments which position single pieces of stock upon a rotary carrier, and to the abutments or members constituting a series of stack-holders into which the pieces are discharged from the carrier.

Another object of the invention is to provide a machine of the class in question with

improved automatic mechanism for arresting its operation in case of a failure of the stock-handling mechanism to discharge a piece of stock in the proper position. In this respect the invention relates particularly to a machine in which a piece of shoe-stock is held, during an operation thereon or during the transferral of the piece from one position to another, in a receptacle-shaped or adapted to conform to the outline or form of the piece and to hold the piece in a definite position.

To this last mentioned end the invention comprises a feeler movably mounted adjacent to the said receptacle, so that the feeler will be engaged and operated by a piece of stock of which any part projects unduly beyond or outside of the receptacle in consequence of failure of the piece to be properly introduced into and seated in the receptacle, and connections between the feeler and power mechanism to interrupt the driving of the machine whenever the feeler is thus operated.

Other objects of the invention, and the features of construction and operation by which they are attained, will be set forth hereinafter, in connection with the description of the illustrated embodiment of the invention.

In the accompanying drawings, Figure 1 is a side-elevation of a machine embodying the present invention; Fig. 2 is a vertical section on the line 2—2 in Fig. 1; Fig. 3 is a plan-view of a portion of the machine, with parts broken away to show the construction more fully; Fig. 4 is a partial plan-view, in section approximately on the line 4—4 in Fig. 1; Fig. 5 is a vertical section on the line 5—5 in Fig. 1, but on a larger scale than the latter figure; Fig. 6 is a section on the line 6—6 in Fig. 1, but on a larger scale; Fig. 7 is a section on the line 7—7 in Fig. 1, but on a larger scale; Fig. 8 is a detail plan-view, partly in section on the line 8—8 in Fig. 7; Fig. 9 is a side-elevation, partly in vertical section on the line 9—9 in Fig. 3, showing particularly the picker-mechanism of the machine; Fig. 10 is a horizontal section on the line 10—10 in Fig. 9, but on a larger scale than the latter figure; Fig. 11 is an elevation looking from left to right in Fig. 10; Fig. 12 is a section

on the line 12—12 in Fig. 9, but on a larger scale than the latter figure; Fig. 13 is a detail plan-view, in side-elevation, of the automatic stop-mechanism of the machine; Fig. 14 is an enlarged detail-view of parts shown in Fig. 13; Fig. 15 is a detail-view, in elevation, of a portion of the automatic stop-mechanism and other parts adjacent thereto; Fig. 16 is a vertical section on the line 16—16 in Fig. 3, but on a larger scale than the latter figure; Fig. 17 is a vertical section on the line 17—17 in Fig. 3, but on a larger scale; Fig. 18 is a detail-view, partly in vertical section, showing particularly the mechanism for raising the top-lifts from the carrier and introducing them into the stack-holders; Fig. 19 is a horizontal section on the line 19—19 in Fig. 2, but on a larger scale than the latter figure; and Fig. 20 is a detail plan-view, showing particularly a portion of the adjusting-mechanism for the stack-holders and the lift-receptacles.

The invention is illustrated as embodied in a machine of the type disclosed in Letters Patent of the United States, No. 1,270,476 granted June 25, 1918, on an application filed January 24, 1916, Serial No. 73,899, by the present applicant. In machines of this type, the stock which is handled consists of pieces of leather or other sheet-metal which have been die-cut in the form of lifts suitable for use in the manufacture of shoe-heels. The operation performed upon these heel-lifts, by the machine in question, is that of grading or sorting them in accordance with a mass-characteristic of the lifts. This operation is performed by operative instrumentalities which are adapted to subject each heel-lift to a heavy pressure over a definite limited portion of its area, and thereafter to discharge the lift into one or another of a series of stack-holders in accordance with the thickness of the lift at said definite portion when subject to the said compression.

While the various features of the present invention are useful, and may be conveniently described as employed, in connection with a machine of the type and performing the specific operation just described, the invention is not limited to embodiment in a particular machine, but its various features are useful in connection with various machines for handling stock of different kinds and for performing various operations upon such stock.

In the illustrated machine the heel-lifts to be operated upon are held in a horizontally extending stack, upon a feed-table, and are withdrawn one at a time from the end of the stack by means of the picker-mechanism hereinafter described. Each lift so withdrawn is then deposited, by the picker-mechanism, in one of a circular series of receptacles provided at the periphery of a

carrier which rotates about a vertical axis. The carrier rotates with a step-by-step movement, thus bringing each lift successively to a point at which it is operated upon by the pressing instrumentalities, and then to a series of points in registration with a series of stack-holders, into one or another of which the lift is discharged from the receptacle. The machine also comprises automatic stop-mechanism for arresting its operation whenever a lift, which has been disengaged by the picker-mechanism, fails to enter and be seated accurately within the appropriate receptacle on the carrier. These several mechanisms will be described in the order of their operation.

In its general structure the machine comprises a hollow column 24, upon the upper end of which is fixed a generally-circular frame-plate 26, while a second stationary frame-plate 28, similar in form, is fixed above the plate 26 and connected rigidly thereto by uprights 30. The feed-mechanism is supported upon a feed-table in the form of a bracket 32, which extends from one side of the frame-structure just above described. The various mechanisms of the machine, with the exception of the stop-mechanism, are actuated by cams mounted upon a cam-shaft 34 which is journaled, in horizontal position, within the lower part of the column 24, as shown in Fig. 2.

The feed-mechanism is shown particularly in Figs. 1, 3, 5, 6, 7, 8 and 9. The stack of lifts X is supported upon a grooved horizontal rail 36, which is mounted above the feed-table 32, and the lifts rest upon this rail with the curved back-portions of their edges downward. The stack of lifts is supported laterally by guides 37, which constitute parts of housings in which two endless chains 38 are arranged with parallel stretches extending alongside the stack. Each chain is provided, at intervals, with spring-pressed pointed pawls 40, which extend inwardly beyond the guides 37 so that they may engage the lateral margins or the side edges of whatever lifts chance to be adjacent to them, and thus drive the stack forwardly as a consequence of the movement of the chains. Owing to the yieldable character of the pawls, additional lifts may be introduced between them by pushing the lifts forward between the chains and into engagement with the rearmost lift in the stack. Fig. 6 shows, at the left, a rear-view of one of the pawls, together with a sectional view of another pawl and the spring 42 by which it is actuated.

The chains 38 are supported by means of sprocket-wheels 46, the wheels being fixed on the upper ends of shafts 48 which are journaled vertically in two frames 44. In order to drive the chains the shafts at the inner ends of the frames are provided, as 130

shown in Fig. 5, with worm-wheels 50 at their lower ends, and these worm-wheels engage right and left-hand worms on a shaft 52 which is journaled transversely on the feed-table 32. The shaft 52 is actuated intermittently, by means of a rocker-arm 54 pivoted on its outer end, this arm constituting a member of a roller-wedge clutch as shown in dotted lines in Fig. 1, the other member of the clutch being a disk 55 fixed on the shaft.

The arm 54 is connected, by a link 56, with one arm of a bell-crank lever 58 pivoted on a bracket 59 depending from the feed-table. The other arm of the lever 58 is forked and provided with rollers which engage an annular groove in a sleeve 64 which is mounted on a shaft 62. The shaft is supported, at one end, in a bearing on the bracket 59. The sleeve 64 is free to slide upon the shaft, but is pressed toward a collar 60, which is fixed on the shaft, by means of a spring 66 coiled about the shaft. The other end of the spring rests against a collar 68 which is fixed to the shaft.

By means which will be hereinafter described, intermittent longitudinal movements are imparted to the shaft 62, and at each left-hand movement, the sleeve 64 rocks the lever 58 in a direction to cause the arm 54, acting through the friction-roller, to impart a partial rotation to the shaft 52. This motion is transmitted to the chains 38 in a direction to cause them to advance the stack of heel-lifts on the rail 36. The movement of the chains is continuous until the movement of the stack is arrested by means hereinafter described, and thereafter the continued movement of the shaft 62 merely causes compression of the spring 66. The opposite movement of the shaft 62 is imparted positively to the lever 58 by means of the collar 60, so as to rock the arm 54 back to its original position.

To adjust the feed-mechanism for lifts of different sizes, vertical movement of the rail 36 is necessary. Accordingly this rail is supported on two stems 70, which slide vertically through the feed-table (Figs. 1 and 5.) Each stem is provided, at its lower end, with a pin 72 which is engaged by the slotted end of an arm 74, and these arms are fixed on a rock-shaft, 76 extending lengthwise of the table. At the outer end of the rock-shaft an arm 77 is fixed, and this arm is provided with a binding-screw 78, which extends through a slot in the flange at the end of the table and constitutes means by which the arm 77 and the rock-shaft may be rocked and then fixed in adjusted position, the rocking movement resulting in vertical movement of the stems 70 and the rail 36.

The adjustment of the feed-mechanism also requires movement of the guides 37 and the feed-chains toward and from each other.

Accordingly the frames 44 are arranged to move transversely on the feed-table, being normally fixed to the table by binding-screws 80 which project through slots in the base-webs of the frames, as shown in dotted lines 70 in Fig. 5. Sockets 82, at the ends of the frames 44, are engaged by levers 84, the hubs of which are loosely mounted, in pairs, on two rods 86 fixed longitudinally beneath the feed-table. The levers 84 of each pair are 75 connected together by gear-teeth 88, so as to have equal movements in opposite directions. By this arrangement the frames 44 are held always parallel and equidistant from the rail 36.

The feed-mechanism of the present machine is similar, in its general characteristics, to that disclosed in the said Letters Patent hereinbefore referred to and it is therefore not claimed broadly as a part of the 85 present invention. It involves, however, an additional feature constituting an improvement over the mechanism of the said application. At the inner end of the stack of lifts, means are provided, not only for supporting 90 them below and laterally, but also for engaging the upper or breast-edges of the lifts to insure their exact alinement and correct location at the time when they are withdrawn from the feed-mechanism by the picker-mechanism. The means in question are shown as embodied in the form of a gage-plate 92 which is carried at the lower end of a stem 94 as shown particularly in Fig. 7. The stem 94 slides vertically in a guide-way 96, 100 and is provided with a pin 98 which engages the forked end of a lever 100. The lever is connected, by a rod 102, with an arm 104, this arm being integral with the hub 106 of one of the levers 84. A gear-segment 107 105 on the hub 106 meshes with a segment 90 fixed on the shaft 76. From this arrangement it results that the adjustment of the arm 77, causes in addition to the adjustment of the other parts of the feed-mechanism, a 110 corresponding adjustment of the position of the gage-plate 92, so that this plate is always in a position to engage the breast-edges of the heel-lifts which the feed-mechanism is otherwise adjusted to handle.

The inner end of the stack of heel-lifts is normally supported by a pair of stop-fingers 108, shown particularly in Figs. 7 and 9. These fingers are pivoted on a stud 110, which is mounted in inclined position on the feed-table, and the fingers are provided with depending arms which are connected, by links 112, with a sleeve 114. This sleeve slides upon a rod 116 which is fixed on the feed-table at a right-angle to the stud 110. The sleeve 114 is connected, by links 118, with an arm 120 which projects from a sleeve 122, and the sleeve is journaled on a rod 124 which is fixed beneath the feed-table. A second arm 126, depending from the sleeve 130

122, is connected, by a rod 128, with an arm 130 (Fig. 2) which extends upwardly from a sleeve 131. The sleeve 131 is journaled on a rod 132 fixed in the column 24, and is provided with a depending arm 134 which carries a roller 136 in engagement with a cam 138 on the cam-shaft 34. The cam-mechanism acts, through the connections above described, to swing the stop-fingers 108 away from each other, and out of engagement with the endmost lift of the stack, at the time when this lift is to be withdrawn by the picker-mechanism, while the opposite return movement of the parts is produced by a spring 139 attached to the arm 134.

The inclined position of the stud 110 has the useful result that it causes the stop-fingers, in their movements into and out of operative position, to follow paths in planes inclined to the surface of the lift engaged by the fingers, and remote from the edge of this lift, so that the movement of the fingers cannot be interfered with by accidental engagement with the edge of the lift when the fingers return to operative position. This construction and mode of operation constitute a novel feature of the present invention.

The feed-mechanism of the present machine is provided, like that of the said application, Serial No. 73,899, with means for clamping the lifts at the inner ends of the stack, to support them against the pressure of the picker-mechanism. These means comprise clamp-blocks 140 (Figs. 7 and 9) which are adjustably mounted on slides 142. The slides have bifurcated upper ends, which are guided by a transverse guide-bar 144 fixed above the feed-table. At their lower ends the slides are perforated and threaded to receive a shaft 146 having right and left-hand threads. The shaft 146 is journaled on the feed-table and is provided, at one end, with a pinion 148 meshing with a segmental gear 150 which is pivotally mounted on the feed-table. The gear 150 is fixed to a second segmental gear 152, which is engaged by a rack 154 which slides vertically in a bearing on the side of the feed-table.

50 The rack 154 meshes, at its lower end, with a segmental gear 156 mounted on the shaft 62. The gear 156 is yoke-shaped, and is journaled loosely on the shaft, but one of its lateral members is embraced between the fixed collar 68, and a second collar 157 which latter is also fixed to the shaft. By means of co-operating shoulders 160 on the gear and the collar 68, the rotative movement of the gear on the shaft 62 is limited.

55 A torsion-spring 158, interposed between the gear and the collar 157, and secured at one end to the gear, and at the other end to the shaft 62, normally maintains the shoulders 160 in engagement, so that the rotation of the shaft 62 in one direction moves the gear

positively, while opposite rotation of the shaft moves the gear yieldingly through the force of the spring 158.

The above described arrangement is such that rotation of the shaft 62, as transmitted to the gear by the spring 158, causes a downward movement of the rack 154 which, in turn, through the gear-segments 150 and 152 and the pinion 148, causes rotation of the screw-shaft 146 in a direction to move the slides 142 and the clamp-blocks toward each other and into firm engagement with the heel-lifts, while the opposite movement of the blocks, by which the heel-lifts are unclamped, is caused positively by the opposite rotation of the shaft 62. The rotary movements are imparted to the shaft 62 by means which will be hereinafter described.

Since the clamps have only a short range of operative movement, it is necessary to adjust them, in their original positions, according to the size of the heel-lifts upon which the machine is operating. For this purpose the pinion 148 is connected with the shaft 146 by means of a sleeve 162, which is integral with the pinion and is splined upon the shaft. The sleeve is provided with a knurled head 164, and a compression-spring 168 is interposed between the sleeve and a disk 166 fixed on the end of the shaft; as shown in dotted lines in Fig. 7. When adjustment of the clamps is required, the knurled head 164 may be pulled outwardly, thus sliding the pinion out of engagement with the gear-segment 150, and the head 164 may then be rotated in one direction or the other to move the clamps toward or from each other prior to the engagement of the pinion by the gear.

The picker-mechanism is shown particularly in Figs. 3, 9, 10, 11 and 12. A member 170 of the frame of the machine supports the bearings of a horizontal shaft 172, upon the inner end of which is mounted a rotatable multi-picker member comprising four radial arms 174. Each of these arms constitutes a tubular guide-way in which one of the pickers is supported and guided.

Each picker has a shank mounted in one of the guideways 174, this shank comprising a central rod or stem 176, on the inner end of which is fixed a collar 178 which fits and slides within the guideway. Near the outer end of the shank a sleeve 180 is fixed upon the stem, and is provided with elongated gear-teeth 182 which also fit and slide within the guideway. At the outer extremity of the shank is a head in which are secured four curved claws 184. These claws project helically from the head, that is in such a direction that they may be introduced into a heel-lift by a helical movement like that of a cork-screw. Each claw consists of a piece of wire bent into helical form and sharpened at one end. The head in which the

claws are fixed comprises an inner cylindrical member 186, which is integral with the stem 176 and is split to permit a slight resilient expansive movement. The claws 5 are seated in helical grooves in the member 186, and are closely embraced by a collar 188. A screw 190, threaded into the end of the stem, is provided with a conical head engaging a corresponding conical perforation in the member 186, and when this screw 10 is driven home, it expands that member so as to cause the claws to be securely clamped against the inner surface of the collar 188. Upon loosening the screw the collar may be 15 removed and the claws may then be readily removed for replacement or sharpening.

For the purpose of imparting longitudinal movements to the picker, a sleeve 192 is mounted on the stem 176, and a compression-spring 194 is interposed between the sleeve 180 and a washer 196 which is splined to the stem and rests against the sleeve 192. This spring acts to retain the sleeve 192 normally 20 against the collar 178, as shown in Fig. 10. The sleeve has a lateral projection which extends through a longitudinal slot in the guideway 174, and carries a roller 198. This roller traverses a circular pathway 200 which is formed on the face of a stationary disk 202. 25 The disk is provided with a hub 204 which serves as a bearing-sleeve for the shaft 172 and which is fixed in the frame-member 170.

The engagement of the roller with the pathway retains the roller normally in its 30 innermost position, as in Fig. 10, but, for the purpose of producing the outward movements of the roller by which the picker is advanced, the pathway is interrupted at two points by gaps to permit the engagement of 35 the roller with two actuating-levers. One of these levers, 206, is provided with two lugs 208 which normally form a continuation of the pathway 200, as shown by dotted lines in Fig. 9. This lever 206 is pivoted on a 40 stud 209, and its lower end is connected, by a rod 210, with an arm 212 projecting upwardly from a sleeve 214 which turns on the rod 132, as shown in Fig. 2. Depending 45 from the sleeve 214 is an arm 216 which carries a lever 218 engaging a cam 220 on the cam-shaft 34. The cam-mechanism just described is so timed that when one of the rollers 198 is moved into the space between the lugs 208 and has come to rest with the parts 50 in the position of Fig. 9, the upper end of the lever 206 is swung toward the left, thus advancing the picker into engagement with the exposed surface of the endmost lift in the stack on the feed-table.

55 At the same time it is necessary to advance the picker, which is in the lowermost position, this picker being that which has received a lift from the feed-mechanism and which is in position to deposit the lift in one of the receptacles hereinafter described.

For the purpose of advancing this lowermost picker, a second actuating-lever 222 is employed, this lever being mounted upon a stud 224 and having lugs similar to the lugs 208 which enter a gap in the lower part of the 70 pathway 200 and form a continuation thereof.

The lever 222 is actuated by connection with the lever 206. For this purpose it is 75 provided with an arm 226 which is connected, by a link 228, with the upper arm of the lever 206.

In order to lock the picker-supporting arms 174 securely against any rotative movement during the advancing and retracting movements of the pickers, each arm is provided with two flanges 230, which are located on opposite sides of the slots through which the rollers 198 move and are shaped to conform to the path of movement of the 80 lugs 208 on the levers 206 and 222 and to embrace said lugs when said levers are actuated.

The rotative movements are imparted to each picker by a rack 232, (Figs. 9 and 10) 85 which is mounted to slide in a transverse bearing on the corresponding arm 174. The rack meshes with the teeth 182 on the shank of the picker. The movements of the rack are derived from the levers 206 and 222. 90 For this purpose, a bell-crank lever 234 is mounted on a stud 236 on the arm 174, and is connected, by a pivot 238, with one end of a slidable plate 240, which rests against the outer surface of the rack and retains it in 100 its bearing. The other end of the plate 240 is connected, by a stud 242, with a second bell-crank lever 244 which is mounted on a stud 246 on the arm 174. The rack is longitudinally bored to receive a tension-spring 105 248, of which one end is fixed to a pin 250 in the rack, while the other end is attached, by a pin 252, to the bell-crank lever 244.

In Fig. 9 the rack corresponding to that 110 picker which is about to receive a heel-lift is in its upper position, where it is retained by the friction of the parts. After the picker has been advanced, as above described into engagement with a lift, the continued movement of the lever 206 results in 115 a sliding movement of the sleeve 192 on the stem 176, and in the compression of the spring 194. At the same time a lug 254 on the upper end of the lever engages the upper arm of the bell-crank lever 234 and 120 rocks this lever in a direction to move the plate 240 downwardly. Owing to the tension of the spring 248 the rack 232 participates in the downward movement, causing the picker to rotate so that the claws 184 125 are introduced into the substance of the lift. This rotation continues until the head of the picker has been drawn into firm engagement with the surface of the lift, whereby further rotation is arrested. The continued down- 130

ward movement of the plate 240 thereafter is permitted by elongation of the spring 248.

The contrary rotation of the picker, to release the lift when the picker occupies its discharging position, is produced by engagement of the corresponding bell-crank lever 244 by a lug 256 on the lever 222. The lever 244 has an arm which engages the end of the rack and thus moves it positively to its original position.

For convenience in disassembling the picker-mechanism, for the purpose of replacing or sharpening the claws, or for other repairs, the plate 240 is arranged to be easily disengaged from the lever 244. The stud 242 is provided with a flange 258 which is engaged by a plate 260, said plate being laterally slotted to receive the shank of the stud, as shown in dotted lines in Fig. 9.

20 The plate 260 is mounted to swing about a pivot-screw 262 and is provided, on its inner surface, with a boss 264 which normally is held in engagement with a recess in the plate 240 by the action of a spring 261 bearing against the plate 260. When the mechanism is to be disassembled, the plate 260 may be swung out of engagement with the stud 242, whereupon this stud may be withdrawn from the lever 244. The plate 240 25 may then be swung out of engagement with the rack, which may then be removed from its bearing and the picker can then be withdrawn from the arm 174.

The intermittent quarter-rotations are imparted to the shaft 172 by mechanism shown in Figs. 2, 3 and 4. A skew-gear 266, on the outer end of the shaft 172, meshes with a skew-gear 268 on the upper end of a shaft 270 which is journaled on the frame of the machine. The lower end of the shaft is connected, by a train of idler-gears 272 (Fig. 4), with a gear 274 fixed to a hub 276. This hub turns about a tube 278 which is fixed in upright position at the middle of the main frame of the machine.

The gear 274 has intermittent partial rotations which are imparted to it by the same mechanism which produces the sliding and rotative movements of the shaft 62 hereinbefore described. This mechanism is shown particularly in Figs. 2, 4 and 17. The shaft 62 extends alongside the gear 274, and upon it a sleeve 280 is fixed. This sleeve is provided with a series of partly annular gear-teeth 282, which are adapted to mesh with the teeth of the gear 274 and which also mesh with the teeth of a gear-segment 284. The segment is carried on the upper end of a lever 286 pivoted on the frame of the machine. At its lower end the lever carries a roller 288 which engages a cam 290 on the cam-shaft 34.

A locking-member, comprising a partly cylindrical body 292 and end-members 294, is loosely mounted on the shaft 62, which is

embraced by the end-members. Longitudinal movement of the locking-member is prevented by the engagement of its ends with bosses on the frame-plate 26, as shown in Fig. 4. The part 292 engages longitudinal shoulders on the sleeve 280, as shown in Fig. 17, so that, while there may be relative longitudinal movement of these parts, they are constrained to rock together about the axis of the shaft 62, the shaft also being rocked by its connection with the sleeve 280.

To produce rocking-movements of the parts above described, an arm 296 projects integrally from one end of the locking-member 294, and is connected, as shown in Fig. 2, with a rod 298 pivoted, at its lower end, to a cam-lever 300. This lever carries a roller 302 which engages a path in the cam 290.

The mechanism just described operates as follows: The parts are shown in the drawings in the positions assumed by them at the end of a partial rotative movement of the gear 274, this movement being in the direction of the arrows in Fig. 4. The next movement of the mechanism consists of a rocking-movement, produced through the lever 296 and the cam-mechanism connected therewith, and this rocking-movement, in addition to causing a partial rotation of the shaft 62 for the purposes which have been hereinbefore described, causes the teeth 282 on the sleeve 280 to disengage the gear 274 while the latter is engaged by a series of locking-teeth 304 on the locking-member 292. By these teeth the gear 274 is temporarily locked against rotation. A longitudinal return movement is then imparted to the sleeve 280, by the operation of the gear-segment 284 and the cam-mechanism connected therewith. At the end of this return movement, a reverse rocking-movement is imparted to the locking-member, whereby the gear 274 is unlocked and is engaged again by the teeth on the sleeve 280. The sleeve is then again moved longitudinally so as to cause a partial rotation of the gear 274. Since the sleeve 280 is fixed to the shaft 62, it imparts to the latter its longitudinal movements, which are utilized as hereinbefore described.

The stock feeding and handling mechanisms which have been explained in the foregoing description are not claimed herein since these mechanisms form the subject matter of a divisional application Serial No. 223,220, filed March 18, 1918.

The heel-lifts are discharged by the picker-mechanism into a series of receptacles formed at the periphery of a circular carrier which rotates about the vertical tube 278. This carrier comprises a circular plate 306, which extends integrally from the upper end of the hub 276 of the gear 274, so that the intermittent partial rotations of the

gear are imparted to the carrier, and thus each lift has a step-by-step movement through the machine. At the periphery of the plate 306 are fixed a series of plates 308, which constitute supports upon which the lifts may rest in horizontal position, each such support being constituted, as shown in Figs. 3 and 20, by adjacent portions of two contiguous plates.

10 The lift-receptacles are completed by abutments, in the form of fingers, arranged in pairs 310 and 312 which are adapted to engage the edges of the heel-lift resting upon the support. The fingers 310 engage the 75 curved rear edge of the heel-lift, while the fingers 312 engage the breast-edge. These fingers are normally fixed in place, in accordance with the size of the lifts upon which the machine is operating, but they are adjustable to different sizes of lifts, by means hereinafter described.

The fingers are so adjusted as to closely confine the heel-lift against lateral or rotative movement in the plane of its extension, and accordingly, when the lift is introduced into one of the receptacles by the downward advancing movement of the lowermost picker, as before described, the subsequent reverse rotation of the picker causes 80 disengagement of the claws with the lift, since the fingers prevent this rotation from being shared by the lift. Upon the succeeding retraction of the picker, the lift is therefore left lying in the receptacle.

85 It may sometimes happen that, owing to the accidental inclusion of a heel-lift of the wrong size, or through other causes, a lift is inaccurately deposited in the receptacle. In such a case some portion of the lift will 90 project from the receptacle and lie above or on top of one or another of the fingers 310 and 312. The automatic mechanism for interrupting the operation of the driving mechanism hereinbefore referred to is adapted to detect such a condition and to arrest 95 the operation of the machine before any damage can result, and it is also adapted to yield and permit the arrest of the machine in case any unusual resistance is encountered in its operation. This stop-mechanism is shown particularly in Figs. 2, 3, 13, 14, 100 15 and 19.

The machine is driven by a power-shaft 105 314 which is mounted in bearings 316 at the top of the frame of the machine. Two pulleys 318 and 320 are mounted on the shaft 314, and a belt 322 connects these pulleys with any suitable source of power. The pulley 318 is a loose pulley, while the pulley 320 is normally coupled to the shaft so as to 110 constitute a driving pulley. The power-shaft is connected, by skew-gears 324 and 326, with a vertical shaft 328 which projects downwardly through the tube 278. At its 115 lower end the shaft 328 is connected, by

gears 330, with a vertical worm-shaft 332. This shaft is provided with a worm which meshes with a worm-gear 334 on the cam-shaft 34, and by these means the cam-shaft is rotated constantly during normal operation of the machine. Upon the power-shaft 314 is mounted a sleeve 336, (Fig. 19) which is free to slide upon the shaft, but which is provided with shoulders which coöperate with shoulders on a collar 338 keyed to the shaft, so that the sleeve cannot rotate on the shaft. A disk 334, integral with the hub 336, is provided with beveled lateral projections 342 at its periphery, which coöperate with similar recesses in a ring 333 fixed inside the rim of the pulley 320. A compression-spring 340, coiled about the hub 336, normally forces the disk 334 from left to right, thus maintaining the inclined projections and recesses in engagement so 85 that the rotation of the driving-pulley is transmitted, through the disk and the hub, to the collar 338 and thus to the power-shaft.

The belt 322 is embraced by a forked belt-shipper 344, (Figs. 13 and 14) which is 90 carried at the upper end of the upright arm of a bell-crank lever 346. This lever is pivoted at 348 on the frame of the machine, and is provided with a horizontal arm 350 which is pressed upwardly by a compression-spring 352. The lever thus tends to rock in a direction to shift the belt from the driving-pulley 320 to the loose pulley 318. This movement is normally prevented, however, by a detent 354, mounted on the 100 arm 350, which engages a latch 356 carried by a trip-lever 358. This trip-lever is fixed on a rock-shaft 360, journaled on the frame of the machine. A compression-spring 362, acting against a lug on the trip-lever, tends to rock the latter from left to right, as shown in Figs. 13 and 14, and thus to retain the latch in engagement with the detent, but when the trip-lever is swung in the opposite direction, the shipper-lever 346 is 105 released and thereupon shifts the belt, its movement being terminated by the engagement of an adjustable stop 364, carried by the shipper-lever, with a part of the frame of the machine. 110

In case any unusual resistance to the operation of the machine is encountered, the driving-force transmitted through the beveled projections 342 overcomes the pressure of the spring 340, so that these projections 115 ride out of the recesses, thus permitting a movement of the disk 334 to the left. The disk then engages the upper end of the trip-lever 358 and swings this lever to the left, so as to disengage the latch from the detent 120 354, whereupon the shipper-lever moves as above described and interrupts the driving 125 of the machine.

In order to cause the stop-mechanism to act whenever a heel-lift is not accurately 130

positioned in the receptacle into which it has been discharged by the picker-mechanism, a feeler is employed in the form of a horizontally extending bar 366, which is located just above the path of movement of the fingers 310 and 312, as shown particularly in Figs. 13 and 15. The feeler is located also somewhat to the left of the position occupied by the receptacle at the time of receiving the lift, so that the receptacle is moved under and past the feeler upon the subsequent partial rotation of the carrier. The feeler is carried at the lower end of an arm which is mounted on a horizontal pivot 368 in a bracket 383 depending from the frame-plate 28. Integral with the feeler-arm is an arm 370 upon which is mounted a roller 372 which co-operates with a hook 374. This hook is pivoted at the lower end of a slide-rod 376, which moves vertically in a bearing on the frame and is connected with the forked end of an arm 384 fixed to the rock-shaft 360. The hook is provided with a lug 380 which moves between two pins 382 fixed in the bracket 383. A spring 378 tends to rock the feeler into the position shown in Fig. 15, with the arm 370 in its uppermost position and the roller 372 resting in a notch in the hook 374. At this time the action of the spring 362, tending to rock the arm 384 upwardly, causes the slide 376 and the hook to be drawn upwardly, so that the lug 380 is pressed against the upper pin 382 and the hook is therefore swung to the right so as to engage the roller 372.

With the parts in the positions just described, if the feeler 366 is engaged by any part of a heel-lift which is not properly seated in the lift-receptacle during the movement of the latter from right to left, as in Fig. 15, the feeler is thereby swung to the left, causing the roller 372 to pull the hook 374 downwardly until, by engagement of the lug 380 with the lower pin 382, the hook is swung to the left and releases the roller. The resulting downward movement of the slide 376 and the arm 384 causes the trip-lever 358 to be swung to the left, so as to release the shipper-lever and stop the machine.

To permit the operator to start and stop the machine at will, the hand-lever 388 is pivoted, at 390, on the offset end 392 of the lever 350. The hand-lever is provided, at its lower end, with a pin 394 which engages a lug 396 on the trip-lever. Whenever the operator desires to stop the machine, this is done by swinging the hand-lever from left to right, as in Figs. 13 and 14, thus causing the pin to swing the trip-lever to the left and release the shipper-lever. When the machine is to be started by the hand-lever, the lever is swung in the opposite direction, thus causing its lower end to engage the

shoulder formed by the offset 392 on the arm 350, whereupon the hand-lever causes the shipper-lever to swing to the left and shift the belt to the driving-pulley, while at the same time the detent 354 is engaged by the latch 356, so that the parts remain in operative position after the release of the hand-lever.

After the lift-receptacle is moved away from the picker-mechanism and past the feeler of the automatic stop by the rotation of the carrier, the next operative position in which it comes to rest is that in which the lift is subjected to the operation of the pressure-applying members hereinbefore mentioned. These parts of the machine are substantially the same as those employed in the machine of the said Letters Patent hereinbefore referred to, and are not, therefore, claimed herein, although they will be briefly described to give a clear understanding of the operation of the machine as a whole. As shown in Fig. 16, the upper pressure-member is in the form of an adjustable stationary pin 398, fixed to the frame-plate 28 in such a position that its lower end is directly above a point near the middle of the lift. The lower pressure-member 400 is fixed in the upper end of a stem 402 which slides through a bearing-sleeve 404 fixed in the frame-plate 26. A sleeve 406 is slidably mounted at the lower end of the stem 402, its downward movement being limited, however, by shoulders on the sleeve and stem. A strong compression spring 408 occupies a bore in the stem and engages, at its lower end, an adjustable plug 410 screwed into the sleeve 406.

A lever 412 is connected with the sleeve 406 through links 413, and the outer end of the lever is supported by a link 414, of which the upper end is pivoted to the frame-plate 26. The inner end of the lever 412 is pivoted to one of a series of arms 420 which radiate outwardly, as shown in Fig. 2, from a hub 418 which is slidably mounted on the fixed tube 278 at the center of the column 24. These arms support, at their outer ends, a ring 422 which, by its vertical movements, actuates certain parts of the mechanism hereinafter described. The vertical movements are imparted to the hub and the arms by cam-mechanism. For this purpose an arm 424 depends rigidly from the hub and is slotted, at its lower portion, to span the cam-shaft 34 and thus prevent rotation of the hub. Upon this arm a roller 426 is journaled, and this roller engages a path in a cam 428 fixed on the cam-shaft.

When the lever 412 is raised, the lower pressure-member 400 rises through the opening formed at the central part of the lift-support, and presses the heel-lift against the pin 398 with a pressure which is determined by the spring 408, this spring yielding when

the predetermined pressure has been reached, and permitting the sleeve 406 to slide on the shank 402.

The pressure to which the heel-lift is subjected, on a limited portion of its area, is so severe as to reduce the substance of the lift approximately to a standard density regardless of its original density, so that the thickness of the compressed portion is then practically a measure of the mass per unit of area in the lift, this being the "mass-characteristic" in accordance with which the machine is designed to grade and sort the lifts. The mass-characteristic so measured determines the stack into which the lift is subsequently discharged by the machine, and this is effected through the agency of a gage-pin 430 associated with each lift-receptacle. This pin slides through a vertical bearing on the carrier-plate 306, and it is retained frictionally by a spring-pressed plug 432. A lever 434 is pivotally mounted at the upper end of the bearing-sleeve 404, as shown in Fig. 16, and this lever spans, and is pivoted to, the upper end of the stem 402 by a transverse pin 436 which passes through slots in the bearing-sleeve. The lever 434 carries, at its inner end, a screw 438 which is moved into engagement with the gage-pin by the upward movement of the lever 434, and since this movement has an amplitude determined by the upward movement of the stem in compressing the heel-lift, the screw 438 acts to raise the gage-pin in its bearing through a distance inversely proportionate to the thickness of the heel-lift under compression.

The stacks of graded heel-lifts are supported in a series of stack-holders, each of which comprises four vertical rods which 40 constitute abutments by which the edges of the stacked lifts are engaged. The inner two rods 440, as shown in Fig. 20, engage the curved rear edge of the lift, while the outer rods 442 engage the breast-edges.

45 The stack-holders are located directly above the successive positions occupied by the lift-receptacles when the carrier comes to rest. The lowermost lift in the stack is supported by pawls 444, which are pivoted to the lower ends of the rods and which may be pressed outwardly to permit the vertical movement of a lift into the bottom of the stack. The return movements of the pawls are produced by springs 446, as shown in Fig. 17.

Beneath each stack-holder is located a plunger comprising a head 448 mounted at the upper end of a stem 450 which slides vertically through a sleeve 452 but is held 60 from rotation relatively thereto. The sleeve is mounted to turn in a bearing 454 supported at the periphery of the frame-plate 26, and vertical movement of the sleeve is prevented by a collar 456 screwed on its lower end. The ring 422, which has inter-

mittent vertical movements, as before described, is provided with a lug 460 adjacent the end of each of the plunger-stems 450. At the lower end of the stem is fixed a collar 462 provided with a flange 463 located below the lug 460. A second flange 464 on the collar is so located, as shown in Fig. 4, that it is normally out of the path of upward movement of the lug, but may be brought into that path by a partial rotation of the stem 450. Rotation of the stem, for the purpose just mentioned, is produced by the engagement of the gage-pin 430 with a lug 468 at the inner end of an arm 466 which is integral with, and projects inwardly from, the sleeve 452. The lugs 468 are of graded heights, so that each one may be engaged by a gage-pin at a different level, and thus the lift in the receptacle may be discharged into one or another of the stack-holders according to the position of the corresponding gage-pin. In the normal position of the parts, which is shown at two planes in the upper right-hand portion of Fig. 4, the arm 466 is held in retracted position by a spring 474, of which one end is attached to the frame and the other end to a pin on the arm. At this time a beveled lug 476 on the flange 464 rests against a stop-pin 458 which projects downwardly from the frame-plate 26 at one side of the bearing 454, and at this time the flange 464 is out of the path of movement of the actuating-lug 460. When the gage-pin 430 encounters the lug 468, however, it acts, during the last part of the 100 rotative movement of the carrier, to swing the arm 466 to the position shown, in different planes, at the top and at the right-hand portions of Fig. 4. The sleeve 452 is thus turned, and with it the stem 450, through connections hereinafter described. The flange 464 is then engaged and raised, at the succeeding movement of the ring 422 and the lug 460, so that the head 448 rises through the opening in the lift-support and 110 raises the lift into the stack-holder.

In order that the gage-pin may be raised, after the operations just described, to permit it subsequently to pass by the lugs 468, an arm 470 is fixed to the upper end of the stem 450, and this arm has an offset extremity 471 which engages the lower end of the gage-pin near the upper part of the rising movement of the plunger, as shown in Fig. 18, so as to raise the pin, which is then retained by the friction-plug 432. A post 472, fixed at its lower end in the arm 466, slides through an opening in the arm 470 so as to cause the plunger to turn with the sleeve 452.

During the subsequent descent of the plunger, which is positively insured by engagement of the actuating-lug 460 with the flange 463, the arm 466, which is then out of engagement with the gage-pin 430, is pre- 130

vented from swinging back by the engagement, with the stop-pin 458, of the rear extremity 478 of the flange 464, as shown at the top of Fig. 4, but when the plunger 5 reaches its lowermost position these parts become disengaged and the spring 474 rocks the arm 466 back to its normal position.

A cam 480 is mounted on the frame-plate 28 near the front of the machine, and this 10 cam has an inclined lower surface which engages the upper end of each gage-pin as it moves by and acts to depress the gage-pin prior to the renewed operation thereon of the pressure-applying mechanism above described.

The machine is organized to operate at one time upon heel-lifts all of the same size or outline. Whenever it is desired to change the size of the lifts, it is necessary not only 20 to adjust the feed-mechanism, as hereinbefore described, but also to adjust the abutments which determine the positions of the lifts on the lift-supports, and also the positions of the abutments or rods which constitute the stack-holders into which the 25 sorted lifts are discharged.

One object of the present invention, as aforesaid, is to provide means whereby such adjustment may be made simultaneously at 30 a plurality of positions or stations in the machine and in a convenient and simple manner. Mechanism for adjusting the stack-holders is shown particularly in Figs. 1, 3, 17 and 20. Each of the rods 442 is 35 fixed, at its lower end, to an arm 482 of a three-armed lever which is mounted on a vertical stud 486 supported in a projection 488 from the frame-plate 28. Each of the levers has also a rearwardly extending arm 484, which supports one of the rods 440. The third arm 490 of each lever is provided 40 with a pin 492 which enters a slot in one of a pair of disks 494 and 496. These disks are supported, in horizontal position, on an 45 annular bearing 498 mounted on, and concentric with, the frame-plate 28, as shown in Fig. 17. The three-armed levers are arranged in pairs, one above the other, and the 50 upper lever of each pair is articulated with the disk 494, while the lower is articulated with the disk 496.

By rotary movement of the two disks in opposite directions the three-armed levers of each pair may be swung in opposite directions, so as to move the rods supported thereby in opposite directions and through 55 proportionate distances. The pivot-studs 486 are so located with respect to the lift-supports that the rods move through curved 60 but approximately radial paths, and accordingly the described movements not only adjust the rods to receive lifts of different sizes, but they also keep the rods always in such positions that the lifts shall be held by 65 them in approximately similar positions with

respect to the central point of the lift-support and the axis of the plunger by which the lift is raised into the stack-holder.

The opposite rotary movements of the adjusting-disks 494 and 496 are produced by means shown in Figs. 1 and 3. The disks are cut away, at one point, to afford a space for an adjusting-screw 500, which is threaded right and left at its opposite ends. The screw is threaded into two nuts 502 and 504, which are pivotally mounted in the disks 494 and 496 respectively. A worm-gear 506, fixed at the middle of the screw, is engaged by a worm 508, on a shaft 511 which is journaled in a bearing-yoke 510 80 fixed on the frame-plate 28, as shown in Fig. 1. A key may be applied to the squared end of the shaft 511, and by rotation of the shaft one way or the other all of the stack-holders may be adjusted simultaneously in 85 accordance with the size of the heel-lifts upon which the machine is to operate.

The fingers 310 and 312 which position the heel-lifts on the lift-supports are adjusted by mechanism similar to that just 90 described. They are mounted on three-armed levers each having, as shown in Fig. 3, an arm 512 which supports one of the fingers 312, an arm 514 which supports one of the fingers 310, and an arm 516 which is 95 articulated with a bifurcated projection 518 from one of two adjusting disks 520 and 522. These disks are mounted, as shown in Fig. 17, in a bearing 524 on the carrier-plate 306. The fingers 310 and 312 may 100 accordingly be adjusted, through proportionate distances, by opposite rotation of the disks 520 and 522, and this rotation is produced by mechanism similar to that associated with the disks 494 and 496, and including a shaft 526 having a squared end which may be turned by a suitable key. By these means the lift-receptacles are so 105 adjusted that whatever the size of the heel-lift it will be positioned on the support so 110 that the point engaged by the compressing-members is located approximately in an analogous position with respect to the outline of the lift.

To insure a firm support of the heel-lift 115 in the receptacle, and also certainty of operation of the ejecting-plunger upon the lift, it is desirable that the lift, whatever its size, be supported and engaged at its margin. Accordingly, the lift-support is formed as 120 shown in Fig. 3, with a series of approximately radial inward projections and an intervening series of approximately radial slots, while the head 448 of the ejecting-plunger is formed with a series of approximately 125 radial webs which correspond in form with the slots in the lift-support and extend throughout a space at least equal to the superficial area of the largest heel-lift which may be operated upon. These 130

webs are also so arranged as to avoid contact with the fingers 310 and 312 and the lever-arms upon which they are mounted. As shown in Fig. 3 the webs of the ejecting plungers are not in a position to register with the slots, but it will be understood that they are brought to such position by the partial rotation of the plungers which occurs prior to their rising-movement, 10 through the operation of the gage pins 430 as hereinbefore described.

While the several features of the present invention have been illustrated and described as employed in conjunction, and in 15 a machine for performing a particular operation upon heel-lifts, it will be understood that the several novel features are not limited to such conjoint and particular employment, but that the invention may be 20 embodied in various other forms within the scope of the following claims.

What is claimed as new, is:—

1. A stock-handling machine having, in combination, a support for the stock provided with slots extending in generally radial directions from the central part of that portion of the support on which the stock rests; and a plunger for discharging the stock from the support, having webs formed to pass through said slots and engage the surface of the piece of stock.

2. A stock-handling machine having, in combination, a support for the stock provided with slots extending in generally radial directions from the central part of that portion of the support on which the stock rests; and abutments, located and adjustable in the spaces between said slots, for engaging the periphery of the stock to locate it in a predetermined position on the support.

3. A stock-handling machine having, in combination, a support for a piece of stock, comprising separate members lying in a common plane and adapted to engage the surface of the stock at different parts extending to the periphery thereof; abutments arranged to engage the periphery of the stock at separated points to locate the stock on the support; and a plunger, for discharging the stock from the support, having webs arranged to enter the spaces between said members of the support and said abutments and to engage the stock at intermediate parts extending to the periphery thereof.

4. A stock-handling machine having, in combination, a support on which the piece of stock lies; a plurality of abutments arranged to engage the periphery of the piece at separate points to locate the piece with a given point therein at a given point on the support; and means for adjusting said abutments toward or from each other and said point on the support through substan-

tially proportionate distances, so as to adapt the abutments to coöperate with pieces of different sizes but similar forms and to locate such pieces similarly with respect to said given points.

5. A stock-handling machine having, in combination, a support on which a piece of stock lies; a plurality of abutments arranged to engage the periphery of the piece at separate points and to locate the piece on the support; and means for adjusting the abutments simultaneously through approximately proportionate distances toward or from a fixed point on the support.

6. A stock-handling machine having, in combination, a support on which a piece of stock lies; two abutments arranged to engage the breast-edge of the piece, and two abutments adapted to engage the back-edge of the piece, at separate points to locate the piece on the support; arms carrying the several abutments respectively and pivoted at the sides of the support; and adjusting means for swinging all of said arms simultaneously through equal angles to move the abutments toward or from each other.

7. A stock-handling machine having, in combination, means for holding a plurality of pieces of stock, similar in form, at a plurality of different stations, said means comprising abutments which engage the peripheries of the pieces; and means for simultaneously and proportionately adjusting the positions of the abutments at a plurality of said stations, to adapt the machine for operation upon stock of different sizes.

8. A stock-handling machine having, in combination, means for holding a plurality of stacks of pieces of stock, said means comprising elongated abutments which engage the edges of the pieces, and means for moving said abutments simultaneously in a plurality of the stack-holders, toward or from each other to adjust the stack-holders for stock of different sizes.

9. A stock-handling machine having, in combination, a rotary carrier adapted to support pieces of stock at a series of positions, on its periphery; abutments mounted on the carrier, at each of said positions, for locating the pieces of stock accurately thereat; and means, for adjusting said abutments simultaneously at all of said positions, comprising an annular member connected with the abutments and mounted on, and rotatable relatively to, the rotary carrier.

10. A stock-handling machine having, in combination, a rotary carrier adapted to support pieces of stock at a series of positions on its periphery; abutments mounted on the carrier, at each of said positions, for locating the pieces of stock accurately thereat; and means, for adjusting said abutments simultaneously at all of said positions, comprising a pair of annular members con-

ected, respectively, with corresponding abutments in the several sets, the annular members being mounted on the rotary carrier, and means for relatively rotating and fixing the annular members.

11. A stock-handling machine having, in combination, means for supporting similar pieces of stock at a series of circularly-arranged positions; abutments arranged to engage the edges of the pieces at each position; and means, for adjusting the abutments simultaneously at a plurality of positions, to adapt them to receive pieces of different sizes, comprising a circular member connected with the abutments at said plurality of positions and rotatable to move said abutments simultaneously.

12. A stock-handling machine having, in combination, a plurality of stack-holders comprising parallel rods between which pieces of stock are stacked with their edges in engagement with the rods; pivoted arms carrying the respective rods; and means, for adjusting said stack-holders simultaneously, comprising means connected with said arms and adapted to move them simultaneously through proportionate distances.

13. A stock-handling machine having, in combination, a rotatable carrier for supporting a series of pieces of stock, means for successively subjecting each piece to pressure, a plurality of means for discharging said pieces at different stations, a periodically reciprocating annular member, and means for connecting said pressure means and said discharging means thereto.

14. A stock-handling machine having, in combination, a carrier for supporting a piece of stock, a spring-seated pressure plunger for engaging said piece, an ejector for discharging said piece, a periodically reciprocating member, an unyielding connection between said pressure plunger and said member, and means for connecting and disconnecting said ejector to and from said member.

15. A stock-handling machine having, in combination, a carrier for supporting a piece of stock, a plunger for subjecting said piece to pressure, means for actuating said plunger into engagement with said piece and a spring associated with said plunger for determining the pressure to which the piece is subjected.

16. A stock-handling machine having, in combination, a stationary frame, a movable carrier for supporting a piece of stock, a plunger slidable through said frame for subjecting said piece to pressure, a link depending from said frame, a reciprocating member, and a lever, having its end respectively connected to said link and said reciprocating member, adapted to support and actuate said plunger.

17. A stock-handling machine having, in

combination, a movable carrier for supporting a piece of stock and having an opening over which the piece rests, a stationary stop of relatively restricted area disposed above the opening in said carrier, and a movable plunger adapted to be projected through said opening for raising the piece of stock against said stop and subjecting it to pressure over an area corresponding to that of said stop.

18. A stock-handling machine having, in combination, a movable carrier for supporting and intermittently advancing a series of pieces of stock, said carrier having a plurality of spaced openings over which the pieces rest, a single stationary stop of relatively restricted area disposed above said carrier and over the path of movement of said pieces as they are advanced, a spring-seated plunger actuated in timed-relation to the advance of said carrier and adapted to be successively projected through the respective openings for raising the respective pieces against said stop and subjecting them to like pressures.

19. A stock-handling machine having, in combination, a movable carrier having a plurality of openings over which a series of pieces of stock rest, a plurality of rotatable and reciprocable ejectors disposed at a series of stations beneath said carrier, a periodically reciprocating actuating member; and means for rotating said ejectors into operative relation with said actuating member whereby said ejectors are reciprocated through the respective openings to discharge said pieces from said carriers.

20. A stock-handling machine having, in combination, a support for a piece of stock, an ejector for discharging said piece from said support, a reciprocating actuating mechanism, means for rotating said ejector into operative relation with said actuating mechanism whereby said ejector is actuated to discharge the piece from said support.

21. A sorting machine having, in combination, a rotatable carrier for supporting a series of pieces of stock, means for determining a characteristic of said pieces, means for indicating the determination of each piece, a plurality of annularly arranged ejectors, a reciprocating annular member for actuating said determining means and ejectors, and means controlled by said indicating means for selectively establishing an operative connection between one or more ejectors and said reciprocating actuating member.

22. A stock-handling machine having, in combination, a support for the stock provided with substantially radial slots extending from the central part of that portion of the support on which the stock rests; adjustable means located between the slots for centrally positioning the stock; and means

having webs formed to pass through said slots for engaging the surface of the stock and removing it from the support.

23. A stock-handling machine having, in combination, a carrier for supporting pieces of stock at a series of positions; means disposed at said positions for accurately locating the pieces thereat, and relatively adjustable means mounted on said carrier and associated with all of said locating means for effecting the simultaneous adjustment thereof.

24. A stock-handling machine having, in combination, a carrier for supporting pieces of stock at a series of positions; abutments disposed at said positions for accurately locating the pieces thereat; relatively adjustable members mounted on said carrier and respectively associated with corresponding abutments at each position, and means for effecting relative movement between said members to simultaneously adjust the abutments at each position.

25. A stock-handling machine having, in combination, means for operating on a piece of stock; power mechanism therefor; a receptacle forming a compartment within which the piece is held and supported during the operation thereon; a feeler movable adjacent the boundary of said compartment and adapted to be engaged and operated by any part of the piece of stock which projects unduly beyond said boundary; and connections between the feeler and the power mechanism to interrupt the driving of the machine when the feeler is thus operated.

26. A stock-handling machine having, in combination, a receptacle within which a piece of stock may be supported, said receptacle conforming to the outline of the

piece so as to hold the piece in a definite position; means for moving the receptacle from a receiving-point to a discharging-point; a feeler located adjacent the path of movement of the receptacle so as to be engaged and actuated by any part of the piece of stock which projects unduly from the receptacle; and mechanism operated by any movement of said feeler for stopping the advance of the receptacle.

27. A stock-handling machine having, in combination, a support on which a flat piece of stock may rest; abutments associated with the support, for engaging the edge of the piece and locating it on the support; means for introducing a piece between the abutments; means for moving the support to advance the piece while between the abutments from the stock-receiving position to a stock-discharging position; a feeler located close to the path of movement of said abutments so as to be engaged and actuated by any part of the stock which lies across one of the abutments; and connections between the feeler and the means for moving the support for stopping its advance when the feeler is actuated by engagement with any piece.

28. In a stock-handling machine, stock-holding means having, in combination, a plurality of members arranged to support a stack of pieces of stock and to confine them laterally in all directions by engagement with various points on their edges; and mechanism for moving all of said members simultaneously and proportionately toward or from each other to adjust them to pieces of different sizes.

ERASTUS E. WINKLEY.
